UNITED STATES PATENT OFFICE.

ELMER FRESHWATER AND HAROLD H. CUMINGS, OF PAINESVILLE, OHIO.

TURNTABLE.

Application filed June 27, 1921. Serial No. 430,558.

To all whom it may concern:

Be it known that we, ELMER FRESHWATER and HAROLD H. CUMINGS, citizens of the United States, residents of Painesville, county of Lake, and State of Ohio, have invented new and useful Improvements in Turntables, of which the following is a specification, the principle of the invention being herein explained and the best mode in 10 which we have contemplated applying that principle, so as to distinguish it from other inventions.

Our invention relates to turn-tables and particularly to apparatus of this character 15 adapted to be actuated by means mounted upon the table. Particularly, the invention relates to apparatus by means of which automobile trucks may be turned, the power for turning the table being derived from the 20 truck itself.

The annexed drawings and the following description set forth in detail certain means embodying my invention, the disclosed means, however, constituting but one of the 25 various mechanical forms in which the principle of the invention may be applied.

In said annexed drawings:

Figure 1 represents a plan view of our invention;

Figure 2 represents a vertical longitudinal section, taken in the planes indicated by the lines II--II, Figure 1, a suggestive outline of an automobile truck also being shown in this view;

Figure 3 is a side elevation, upon a reduced scale, showing conditions just after the truck to be turned has come upon the table;

Figure 4 represents the conditions after 40 the truck and table, shown in Figure 3, have been turned through an angle of 180°, and the truck is ready to back off the table;

Figure 5 is a view of the table, as shown in Figure 3, the same having been jacked up 45 and mounted on road-wheels for effecting a change of the base of operations for the table, as hereinafter fully described;

Figure 6 represents a vertical transverse section, taken in the plane indicated by the 50 line VI--VI, Figure 5;

Figure 7 represents a vertical transverse section, taken in the plane indicated by the line VII--VII, Figure 4;

Figures 8 and 9 represent vertical trans- 55 verse sections, taken in the respective planes

indicated by the lines VIII--VIII, and IX--IX, Figure 1;

Figure 10 is a broken vertical longitudinal section, upon an enlarged scale, taken in the plane indicated by the line X--X, Fig- 60 ure 1, the truck and turn-table conditions being those shown in Figure 3;

Figure 11 is a view similar to Figure 10, the truck and turn-table conditions, however, being those represented by Figure 4; 65 and

Figure 12 is a fragmentary transverse vertical section, showing the use of certain locking means hereinafter fully described.

For the purposes of illustration, we have 70 shown in the accompanying drawings the use of the principles involved in our automatic turn-table and shall also hereinafter so describe the same in connection with the building of improved high-ways, in which 75

kind of operation it is customary to establish a base for the spreading or the mixing machine, and to transport to said spreading base or machine the materials to be laid or mixed whence they are spread to form 80 the high-way for a certain distance, 400 feet, for instance, the mixing machine, laying tools and other associated apparatus then being moved to the site of another base for operations, etc. The materials to be worked 85 up are usually brought to the spreading base or the mixing machine along but one high-way and oftentimes, for various reasons, the high-way is not such that it is possible to turn the truck, so that it is necessary to 90 back the same along the high-way for a greater or less distance, after the load has been dumped at the spreading base or into the mixer. For the purpose of illustrating the uses to which our invention may be ap- 95 plied and for showing its construction and principles of operation, we shall describe how its use will obviate the difficulties in road building, hereinbefore mentioned.

Referring to the accompanying drawings, 100 in which the same ordinals refer to the same parts in the several views, an automobile truck is designated by the ordinal 1 having the front wheels 2 and rear or driving wheels 3.

In order to climb upon or descend from 105 our improved turn-table, hereinafter fully described, the truck 1 runs over inclined approach platforms 4 and 5 of any suitable construction. The sub-base for our improved turn-table consists of planking 6 laid 110.

upon the road-way 7. Upon this plank-base 6 we position an upper or main base consisting of a pair of spaced longitudinal I-beams 8 and a pair of longitudinal exterior channels 9 aligned and secured together by means of transverse end I-beams 11 and a series of intermediate transverse I-beams 10. To the top of the base formed from the members 8, 9, 10 and 11, we secure a steel plate 12 upon which is mounted a casting 13 formed with an annular series of teeth 14 so that, in reality, said casting 13 is a horizontally disposed fixed bevel gear, the same having a vertically extended hub 15 forming a bearing surface for a downwardly projecting journal or king-pin 16 formed with an extended rectangular flange 17 secured to I-beams 18 hereinafter fully described. The turn-table proper comprises a platform 20 which is a steel plate secured to a series of spaced longitudinal I-beams 18 aligned and strengthened by means of transverse curved end channels 18' and intermediate transverse I-beams 19. The curvature of the approach platforms 4 and 5 and that of the channels 18' and platform 20 are complementary, as will be plainly seen in Figure 1. The sheet steel platform 20 is formed with four rectangular holes 21 adapted to allow, in the manner and for a purpose hereinbefore fully described, the truck wheels 2 and 3 partially to drop therethru. Secured to the longitudinal I-beams 18 are a series of I-beam sections 22, four as shown, each being secured to an outside I-beam 18 at one end and to one of the intermediate I-beams 18 at the other end, the projections of the outer ends of said I-beam sections 22 forming a right angle. Any other suitable arrangement and number of I-beam sections 22, for the purpose which I shall now describe, will as well be within the spirit of our invention. Depending from each of these I-beam sections 22 are hangers 23 forming bearing members 45 for pins 24 upon which rollers 25 are rotatably mounted. These rollers rest upon the face of the casting 13, within the ring of teeth 14, support the platform 20 and its load, and are made suitably large and strong 50 for the purpose which they serve.

Extending through a horizontal hole in the king-pin 16 and mounted in bearings 27 supported beneath two transverse I-beams 19 disposed upon opposite sides of the transverse medium plane of the platform 20, is a central longitudinal shaft 28 to which is secured adjacent its rear end a bevel gear 28' and to its extreme front end a bevel gear 29 and to its extreme rear end a bevel gear 30. Bevel gears 31 and 32 co-operate respectively with bevel gears 29 and 30, these gears 31 and 32 being secured to transverse shafts 33 and 34 mounted in journal boxes 35 depending from the longitudinal I-beams 18. Secured to the transverse shafts 33 and 34 are

two pairs of corrugated rollers 36 and 37, respectively, said rollers being disposed beneath the openings 21 in the platform 20 and further disposed each between an outside I-beam 18 and an intermediate I-beam 18, all as plainly shown in Figure 1. Rearwardly and forwardly, respectively, of the rollers 36 and 37 are two pairs of idle rollers 38 and 39, respectively, mounted upon short transverse shafts 40 and 41, supported in other journal boxes 35 depending from the I-beams 18. The rollers 36, 37, 38 and 39 are formed with outside flanges 36', 37', 38' and 39', respectively. The purpose of these flanges is to obviate any possibility of the truck slipping or running off the side of the platform 20 when mounting or leaving the same, in the manner hereinafter fully described.

Secured to the transverse shafts 33, 34, 40 and 41, respectively, and immediately outside of the flanges 36', 37', 38' and 39', are ratchet wheels 42, 43, 44 and 45, respectively, Figure 10. Co-operating with these ratchet wheels, respectively, are pawls 46, 47, 48 and 49, hinged upon pins 50 suitably secured to the outside I-beams 18.

A shield for the gear 14 and associated elements, is indicated by the ordinal 51, the same being dependently supported from the I-beams 18 and extending below and around the casting 13 for the purpose of preventing dirt and stones from entering the gear. The ratchet wheels 42, 43, 44 and 45, and the flanges 36', 37', 38' and 39' are each formed with series of respectively aligned holes 53 and 52. Adjacent the ratchet wheels 42, 43, 44 and 45, and secured to the outside I-beams 18, are blocks 54 formed with holes 55, the I-beams 18 also being formed with aligned holes 56. The holes 52, 53, 55 and 56 are designed to accommodate pins 57, for a purpose hereinafter fully described, the holes 55 and 56 being enlarged for a purpose also hereinafter fully described. 110

Secured beneath longitudinal I-beams 8 and channels 9 is a pair of transverse bars 58 adapted to be disposed within suitable channels 66 formed in a pair of the sub-base plank members 6. These transverse bars 58 are secured by means of U-bolts 59 and are formed with end journal surfaces so as to accommodate two pairs of road wheels 60 for a purpose hereinafter fully described, the bars 58 being relatively 120 spaced and positioned properly for this purpose, as plainly shown in Figure 5. The outside channels 9 are formed with holes 61 adjacent the front and rear thereof for receiving a grab-hook or other suitable device 125 secured to the tow-chain 61', for a purpose hereinafter fully described. To the approach platforms 4 and 5 are secured angles 62 which also are removably secured by means of bolts 63 to the outside channels 130

9, Figure 7. The approach platforms 4 and 5 are formed with shoulders 64 and 65 disposed a short distance, substantially $\frac{1}{2}$ ', below the bottom of the curved transverse channels 18', as plainly shown in Figures 3 and 4, for a purpose hereinafter fully described.

10 The invention shown in the accompanying drawings, hereinbefore described and hereinafter claimed, operates and is utilized in the following manner:

Assuming that the loaded truck 1 has come upon the platform 20, over the approach platform 4, and into the position shown in Figures 2, 3 and 10, it is evident that the actuation of the rear truck wheels 3 in the direction indicated by the arrow, Figure 10, will result, through the friction between the corrugated rollers 36 and the 15 drive wheels 3, in the turning of the shaft 33, bevel gear 31, bevel gear 29, and pinion 28'. Inasmuch as the gear casting 13 is fixed, the platform 20, truck 1 and its load will turn upon the rollers 25 to any desired 20 position, for instance, the reversed position of the truck shown in Figure 4. It will be noted, particularly in Figure 10, that the pawls 46 and 48 are so hung as to play idly over the ratchet wheels 42 and 44 during 25 this operation. The respective elements of the table are so scaled and assembled that, during this operation, the front wheels 2 of the truck 1 pass over and ahead of the front rollers 37 and 39. Assuming now 30 that it is desired to back the truck 1 off from the platform 20 and down the inclined approach platform 5, the rear wheels 3 are actuated in the direction indicated by the arrow, Figure 11, the pawls 46 and 48 being 35 now so hung that they oppose the turning movement of the ratchet wheels 42 and 44 and hence the turning movement of the rollers 36 and 38 so that the truck wheels 3 climb up over the rollers 38 and the truck 40 leaves the platform 20. It is evident that during these operations the rollers 37 and 39 and the pawls 47 and 49 have been transferred to the relative positions shown in Figure 11, from the relative positions 45 shown in Figure 10, so that these rollers and pawls are now relatively disposed the same as the rollers 36 and 38 and pawls 46 and 48 of Figure 10, so that the next truck can come up the approach platform 4 and be 50 turned with the platform 20 in the manner hereinbefore described as regards the first truck. Thus the operations are repeated with a minimum loss of time and with no idle movements of the turn-table. Furthermore, 55 if it is desired to approach the platform 20 over the incline 5, the rollers 37 and 39 and pawls 47 and 49, in the arrangement shown in Figure 10, or the rollers 36 and 38 and pawls 46 and 48, in the arrangement shown in Figure 11, will properly act

for turning the table and backing off the load. It is presumed herein for the purposes of illustration, that the truck 1 will back up the road 7 to the mixer or spreading area and there be dumped and then 70 drive off forwardly for a new load of material, passing laterally of the turn-table when driving light thereby.

The purpose of the pins 57 and associated elements is to prevent the rotation of the 75 rollers 36, 37, 38 and 39, as the case may be, when it is desired to drive forwardly off from the platform 20 and at an angle therefrom to the direction by which the platform 20 has been entered, if such a necessity arises. The purpose of the plurality of holes 52 and 53 and the enlarged holes 55 and 56 is to assure the registry of the holes 80 53 and 55 with the minimum turning of the rollers 36, 37, 38 and 39, when endeavoring 85 to effect this registry.

When it is desired to change the base of operations of the turn-table, the same including the main base is jacked up above the sub-base 6 and the road wheels 60 mounted upon the journal ends of the bars 58, being suitably secured by pins 60'. The turn table is then pulled by any suitable power and by means of the tow-line 61' to the 90 desired new location, where, the table again 95 being supported by jacks, the wheels 60 are removed and the table let down upon a sub-base 6.

The purpose of the angles 62 and removable bolts 63 is rigidly to align the table 100 and approaches 4 and 5. When it is desired to transport the table for a long haul, it is evident that the table as a whole can be lifted onto a suitable truck in two units, one unit being the platform 20, rollers 25, member 17, shaft 28 and associated elements, and the other unit being the I-beam and channel base, the casting 13 and associated elements. For such a haul, of course, the approach 105 platforms 4 and 5, sub-base 6 and road 110 wheels 60, would be separate units.

The purpose of the slight clearance between the channels 18' and the shoulders 64 and 65 of the approach platforms 4 and 5 is to allow some flexibility in the turn-table proper when the loaded truck strikes the same, the amount of tilting being limited, however, to about $\frac{1}{2}$ ', an amount not sufficient to do any damage but sufficient to allow the table to turn freely.

120 What we claim is:

1. A turn-table comprising, a platform adapted to accommodate an automobile truck; a base for said platform; a circular gear fixed to said base; a longitudinal shaft 125 provided with a pair of gears adjacent its two ends; a third gear adapted to be turned by said shaft intermediate said pair of gears, said third gear being adapted to co-operate with said fixed gear; a pair of transverse 130

- 4
- shafts secured to said platform and each provided with a gear adapted, respectively to co-operate with said pair of gears; and two pairs of rollers so disposed that each pair are positioned upon the two sides of the platform, and adapted to co-operate with a pair of truck wheels to be turned by the latter, said pairs of rollers being rotatably secured to said transverse shafts, respectively.
5. A turn-table comprising, a platform adapted to accommodate an automobile truck; a base for said platform; a circular gear fixed to said base; a longitudinal shaft 60 provided with a pair of gears adjacent its two ends; a third gear adapted to be turned by said shaft intermediate said pair of gears, said third gear being adapted to co-operate with said fixed gear; a pair of transverse shafts secured to said platform and each provided with a gear adapted, respectively to co-operate with said pair of gears; and four pairs of rollers disposed two pairs upon each side of the platform, adapted, 70 each two pairs to support and accommodate between them, respectively, a pair of truck wheels and to be turned by the latter by frictional engagement, one of each of said four pairs being rotatably secured adjacent an 75 end of said transverse shafts.
6. A turn-table comprising, a support consisting of a plurality of connected longitudinal I-beams and a platform secured thereon and adapted to accommodate an automobile truck; a base for said platform; a member 80 having a circular gear segment and fixed to said base; a king-pin depending from said platform and a co-operating hub member secured to said first-mentioned member; a plurality of rollers supported by and below 85 said I-beams and resting upon said base; a shaft provided with a pair of gears, one of said gears being adapted to co-operate with said fixed gear; a shaft having bearings secured to said I-beams, said last-named shaft being provided with a gear adapted to co-operate with the other of said two gears; and a pair of rollers secured to said last- 90 mentioned shaft and adapted to co-operate with a pair of truck wheels to be turned by the latter.
7. A turn-table comprising, a pair of inclined approach platforms and an intermediate base consisting of a plurality of connected channels and I-beams; a platform rotatably mounted on said base, said approach platforms being formed with inner shoulders upon either of which said platform 95 rests when slightly tilted; and means removably securing the ends of said channels to said approach platforms.
8. A turn-table comprising, a base unit and a turning unit, the base unit consisting 100 of connected channels and I-beams and a circular gear fixed thereto and the turning unit consisting of load rollers, I-beams, a platform, and a transmission including a gear adapted to co-operate with said fixed 105 gear, all removable as a whole from the base unit.
9. A turn-table comprising, a support consisting of a plurality of connected longitudinal I-beams and a platform secured thereon and adapted to accommodate an automobile truck; a base for said platform; a member 110 having a circular gear segment and fixed to said base; a king-pin depending from said platform and a co-operating hub
- member secured to said first-mentioned member; a plurality of transverse roller-supports secured to and between contiguous I-beams; a plurality of rollers supported by and below each of said roller-supports and resting upon said base; a longitudinal shaft provided with a pair of gears, one of said 65 gears being adapted to co-operate with said fixed gear; a transverse shaft secured to said platform and provided with a gear adapted to co-operate with the other of said two gears; and means for driving said last-mentioned shaft and adapted in turn to be actuated by the truck.
10. A turn-table comprising, a support consisting of a plurality of connected longitudinal I-beams and a platform secured thereon and adapted to accommodate an automobile truck; a base for said platform; a member 75 having a circular gear segment and fixed to said base; a king-pin depending from said platform and a co-operating hub member 80 secured to said first-mentioned member; a plurality of rollers supported by and below said I-beams and resting upon said base; a shaft provided with a pair of gears, one of said 85 gears being adapted to co-operate with said fixed gear; a shaft having bearings secured to said I-beams, said last-named shaft being provided with a gear adapted to co-operate with the other of said two gears; and a pair of rollers secured to said last- 90 mentioned shaft and adapted to co-operate with a pair of truck wheels to be turned by the latter.
11. A turn-table comprising, a pair of inclined approach platforms and an intermediate base consisting of a plurality of connected channels and I-beams; a platform rotatably mounted on said base, said approach platforms being formed with inner shoulders upon either of which said platform 95 rests when slightly tilted; and means removably securing the ends of said channels to said approach platforms.
12. A turn-table comprising, a base unit and a turning unit, the base unit consisting 100 of connected channels and I-beams and a circular gear fixed thereto and the turning unit consisting of load rollers, I-beams, a platform, and a transmission including a gear adapted to co-operate with said fixed 105 gear, all removable as a whole from the base unit.

Signed by us this 11th day of June, 1921.

ELMER FRESHWATER.
HAROLD H. CUMINGS.
